PEN HOLDING ATTACHMENT FOR
ENGRAVING MACHINES

Augustine J. Masi, Philadelphia, Pa.

Application November 22, 1948, Serial No. 61,408

8 Claims. (Cl. 33—18)

1

This invention relates to a pen holding attachment for an engraving machine and more particularly for a pantograph engraving machine of the type embodying a vertically disposed chuck which moves horizontally above a work support in accordance with a predetermined pattern supported to one side of the work carried by the work support.

The primary object of this invention is to enable an engraving machine of the type above mentioned to be employed in lettering or the drawing of designs on work supported on the table or work support of the machine.

Another object is readily to convert an engraving machine into a lettering or design reproducing machine without altering the mechanical structure of the machine itself.

The above and other objects may be attained by employing this invention which embodies among its features a shank removably supported in the chuck of a conventional engraving machine for movement in unison with the chuck above the work supported on the table or work support of the engraving machine, an arm carried by the shank and extending radially therefrom, a lever pivoted in the arm below the shank for movement in a vertical arc, said lever extending toward the axis of the shank and a pen holder mounted on the end of the lever beneath the shank and having a pen receiving socket therein which aligns axially with the shank.

Other features include a plunger mounted for vertical sliding movement in the arm and engaging the top of the lever on the side of its pivot remote from the pen holder to limit downward movement of the pen holder, a stem on the plunger extending upwardly through the arm, a thumb-piece on the upper end of the stem in spaced relation to the arm and a compression coil spring surrounding the stem between the top of the arm and the thumb-piece yieldingly to hold the plunger retracted.

Still other features include a tubular pen holder supported adjacent the end of the arm for longitudinal adjustment thereon so that the pen supported in the tubular pen holder may be axially aligned with the axis of the shank.

In the drawings:

Figure 1 is a side view of a conventional engraving machine showing this attachment mounted in the chuck thereof for movement with said chuck above the table or work support of the machine;

Figure 2 is a side view partially in section on a somewhat enlarged scale of this improved attachment;

2

Figure 3 is an end view of the attachment illustrated in Figure 2;

Figure 4 is an enlarged horizontal sectional view taken substantially along the line 4—4 of Figure 2, and;

Figure 5 is a vertical sectional view taken substantially along the line 5—5 of Figure 2.

Referring to the drawings in detail a conventional engraving machine designated generally 10 is equipped with a conventional work support or table 12 and chuck 14 which is mounted to move horizontally above the work support or table 12 in accordance with a pattern 16 supported on one side of the machine in a conventional manner. In employing my invention, the spindle which normally rotates the chuck of the engraving machine is used to support the pen during its movements horizontally above the table or work support 12.

My improved attachment designated generally 18 comprises a shank 20 which is clamped in a conventional manner in the chuck 14, and secured as by a screw 22 to the lower end of the shank 20 is an arm 24 which extends radially from the shank and is equipped with a downwardly extending leg 26, the lower end of which is bifurcated as at 28 for the reception of the penholding lever to be more fully hereinafter described. Extending through the arm 24 in parallel relation to the axis of the shank 20 is a bore 29, the lower end of which opens into a recess 30 which opens into the bottom of the bifurcated portion 28 as will be readily understood upon reference to the drawings. The upper end of the bore 29 opens into a recess 32 which opens through the upper side of the arm 24 and mounted for vertical sliding movement in the bore 29 is a stem 34. The lower end of the stem terminates in a plunger 36 which projects into the bifurcation 28 and forms a stop which limits the rocking movement of the lever to be more fully hereinafter described. Fixed to the upper end of the stem 34 in spaced relation to the top of the arm 24 is a thumb-piece 38, and surrounding the stem between the bottom of the recess 32 and the underside of the thumb-piece 38 is a compression coil spring 40 which serves to hold the stem and the plunger retracted into the recess 30 as will be readily understood upon reference to Figure 2.

Pivotaly supported as at 42 in the bifurcation 28 at the lower end of the leg 26 of the arm 24 to rock in a vertical arc is a lever 44, the longer end of which extends toward the axis of the shank 20, while its shorter end projects below

the lower end of the plunger 36. The end of the lever 44 which lies adjacent the axis of the shank 20 is provided with an arcuate recess 46 which lies substantially concentric with relation to the axis of the shank 20, and entering the recessed end of the lever 44 is a bore 48 for the reception of the supporting bar of the pen holder to be more fully hereinafter described.

Opening laterally through the side of the arm 44 and communicating with the bore 48 is an internally screw threaded bore 50 for the reception of the threaded shank of a thumb-screw 52, the inner end of which is adapted to enter the bore 48 as will be readily understood upon reference to Figure 4.

The pen holder which is used in conjunction with this device is designated generally 54 and comprises a tubular body 56 having an axial bore in which a pen 58 is sealed. Opening radially through the tubular body 56 is an internally screw-threaded opening 60 for the reception of the threaded end of a supporting bar 62 which as illustrated in Figure 4 is received in the bore 48. The inner end of the supporting bar 62 frictionally engages the pen 58 in the pen holder 54. The underside of the lever 44 remote from the recess 46 is curved upwardly as at 64 in order to prevent its contacting the work when pressure is applied to the thumb-piece 38.

In use the attachment is mounted in the engraving machine 10 by entering the shank 20 into the chuck 14. In this position the axis of the pen 58 will align substantially with the axis of the shank 20. Should such alignment fail, it is obvious that by loosening the thumb-screw 52, the bar 62 may be adjusted within the bore 48, and upon again tightening the thumb-screw 52, the pen holder 54 will be held in proper position beneath the lower end of the shank 20 and in vertical alignment with the axis of the chuck 14. With the pen loaded with ink, it will be obvious that the point thereof will ride over the surface of work supported on the table or work support 12, and when it is desired to shift the position of the device without contacting the work, pressure may be applied upon the thumb-piece 38 to rock the lever 44 about its pivot 42 so as to lift the pen 58 clear of the work. Upon releasing pressure on the thumb-piece 38 it is obvious that the pen will return by gravity into contact with the work, and by reason of its pivotal support the pen will be free to follow any slight irregularities in the surface of the work and will in effect float on the surface thereof.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. A pen holding attachment for a pantograph engraving machine having a vertical chuck which moves horizontally above a work support, said attachment comprising a shank removably supported in the chuck for movement therewith, an arm carried by and extending radially from said shank, a lever pivoted in the arm below the shank for movement in a vertical arc, said lever extending toward the axis of the shank, a pen holder mounted on the end of the lever beneath

the shank and having a pen receiving socket therein which aligns axially with the shank, and a plunger mounted for vertical sliding movement in the arm and engaging the top of the lever on the side of its pivot remote from the pen holder to limit downward movement of the pen holder.

2. A pen holding attachment for a pantograph engraving machine having a vertical chuck which moves horizontally above a work support, said attachment comprising a shank removably supported in the chuck for movement therewith, an arm carried by and extending radially from said shank, a lever pivoted in the arm below the shank for movement in a vertical arc, said lever

extending toward the axis of the shank, a pen holder mounted on the end of the lever beneath the shank and having a pen receiving socket therein which aligns axially with the shank, a plunger mounted for vertical sliding movement in the arm and engaging the top of the lever on the side of its pivot remote from the pen holder to limit downward movement of the pen holder, a stem on the plunger extending upwardly through the arm, a thumb-piece on the upper end of the stem in spaced relation to the arm and a compression spring surrounding the stem between the top of the arm and the thumb-piece yieldingly to hold the plunger retracted.

3. A pen holding attachment for a pantograph engraving machine having a vertical chuck which moves horizontally above a work support, said attachment comprising a shank removably supported in the chuck for movement therewith, an arm carried by and extending radially from said shank, a lever pivoted in the arm below the shank for movement in a vertical arc, said lever extending toward the axis of the shank, the end of the lever adjacent the axis of the shank having a concave recess therein which lies substantially concentric about said axis, said lever also having an axial bore entering the end having the concave recess, a tubular pen holder seated in said concave recess and a bar extending laterally from said pen holder and adjustably received in said axial bore.

4. A pen holding attachment for a pantograph engraving machine having a vertical chuck which moves horizontally above a work support, said attachment comprising a shank removably supported in the chuck for movement therewith, an arm carried by and extending radially from said shank, a lever pivoted in the arm below the shank for movement in a vertical arc, said lever extending toward the axis of the shank, the end of the lever adjacent the axis of the shank having a concave recess therein which lies substantially concentric about said axis, said lever also having an axial bore entering the end having the concave recess, a tubular pen holder seated in said concave recess, a bar extending laterally from said pen holder and entering the axial bore and means carried by the lever adjustably to hold said bar in said bore.

5. The combination of claim 4, including a pen, said bar frictionally engaging and retaining said pen in said pen holder.

6. A pen holding attachment comprising a base and means for attaching the base to a support member, a lever pivoted intermediate its ends to said base, one end of said lever being provided with a concave recess, a tubular pen holder seated in said concave recess, a radially extending bar on said pen holder, said lever having an axial bore communicating with said re-

cess, and receiving said bar and combined means carried by said base for limiting the pivotal movement of said lever and for oscillating said lever.

7. The combination of claim 6, including spring means yieldingly urging said last means to a limiting position.

8. The combination of claim 6, wherein said base is bifurcated, said lever being pivoted to said base within said bifurcation, said last means including a plunger bore in said base communicating with said bifurcation, a plunger slidably extending through said plunger bore and engaging said lever opposite its pivot from said recessed end, and a spring yieldingly urging said plunger from said bifurcation.
